UNITED STATES PATENT OFFICE.

FREDERICK WILLIAM McNICHOL, OF ST. JOHN, NEW BRUNSWICK, CANADA.

SHEET-HOLDING ATTACHMENT FOR MUSIC-RACKS.

1,359,816.

Specification of Letters Patent. Patented Nov. 23, 1920.

Application filed April 19, 1920. Serial No. 375,093.

To all whom it may concern:

Be it known that I, FREDERICK W. McNICHOL, a subject of the King of Great Britain, residing at St. John, Province of New Brunswick, Canada, have invented certain new and useful Improvements in Sheet-Holding Attachments for Music-Racks; and I do hereby declare that the following is a full, clear, and exact description of the invention, such as will enable others skilled in the art to which it appertains to make and use the same.

The present invention relates to sheet holding attachments for music racks, for securely holding in view of the performer the sheets of music he is playing.

The principal object of the invention is to provide an attachment adapted for connection to any music rack, that will hold the music sheets in such manner as to permit of the unobstructed view of the same and which is particularly arranged for use for out-door playing.

Another object of the invention is to provide a device, which is capable of adjustment for the holding of music sheets of diversified sizes and which is provided with movable spring-actuated clamping means, for the upper edge of the music sheet.

With the above and other objects in view which will hereinafter appear as the description continues, the invention consists of the novel features of construction, combination and formation of parts as will be hereinafter more fully described and particularly pointed out in the appended claims.

In the accompanying drawings has been shown a simple and preferred form of the invention, it being, however understood that no limitation is necessarily made to the precise structural details herein exhibited, but the right is hereby reserved to any changes, alterations or modifications to which course may be had that come within the scope of the claims without departing from the spirit of the invention or sacrificing the efficiency of the same.

Figure 1 is a perspective view of a music rack illustrating the application of the invention thereto;

Fig. 2 is an elevational view of the device detached from the music rack;

Fig. 3 is an elevational view of the device when in folded or collapsed position;

Fig. 4 is an edge elevational view of the same;

Fig. 5 is a detail view of one of the clips in open position;

Fig. 6 is a magnified elevation of the center bar and pawl members;

Fig. 7 is a detail view of the building cord and center holding clip; and,

Fig. 8 is a perspective view of one of the clips detached from the device.

Referring to the figures by numerals of reference, 1 designates the frame of the music rack which is supported by a suitable standard 2 provided with feet, not illustrated.

The attachment comprises a relatively flat central bar 3 the rear lower face of which is attached by means of the rivets 4 to the strap bracket 5. This bracket 5 is formed with an offset portion 6 which latter is spaced from the bar 3, though it extends in parallel plane therewith. The offset portion of bracket 5 on its outer surface is formed, with studs 7 and 8 which together with the offset portion are apertured for the reception of the wing bolts 9 and 10. These bolts 9 and 10 when adjusted serve to hold the bar 3 upon the music rack 1.

Mounted on the pivot pins 11 and 12 adjacent the lower end of the central bar 3, are the arms 13 and 14 which are connected by the pivot pins 15 and 16 to the outer arms 17 and 18. These arms 17 and 18 have connected to their free ends by means of the pins 19 and 20, the angle members 21 and 22 which carry the sheet holding clips which will now be described. The angle members 21 and 22 are capable of pivotal adjustment of their respective pin connections 19 and 20 and the horizontal leg portions 23 of the angle members 21 and 22 are formed with openings 24 in which are mounted the clips 25 formed of spring metal. The clips 25 are of cruciform construction and the head portions 26 extend at right angles to the body portion of the clips. This head portion is bent over at a slight angle and when the clip body portions are passed through the angle member openings 24, the head portions 26 engage the upper surface of the horizontal leg portions 23 of said angle members, whereby the said clips 25 are held in position. In this manner the clips 25 are not only held in position upon the angle members 21, but they are likewise resultant of such mounting, capable of limited pivotal adjustment thereupon.

The blade springs 27 are riveted as at 28 to the horizontal leg portion 23 of the angle members 21 and

these free ends engage the head portions 26 of the clips 25, serving to tension the body portions of the same downwardly against the lower leg portions 29 of the angle members 21. The outer ends 30 of the clips 25 are upwardly bowed and when the device is in position upon the music rack, the music sheet has its upper edge portion disposed against the outer surface of the lower leg portions 29 of the angle members 21 and beneath the body portion of the clips 25.

The arms 13 and 14 are formed with the rack teeth 31 and 32, and connected to the lower end of the central bar 3 upon the pivot pins 33 are the angularly disposed pawl members 34 and 35. These pawl members 34 and 35 are formed with chisel ends which engage the rack teeth 31 and 32 whereby the arms 13, 14, 17 and 18 are held in position.

In this manner these arms 13, 14, 17 and 18 are capable of adjustment for different sizes of the music sheets.

An elastic cord 37 has one end secured to the upper part of the central bar 3 while its lower end is attached to the angle clip 38. The elastic cord 37, after the music sheet has been inserted under the clips 25, is drawn across the said sheet at its central part and the angle clip 38 engages the music frame bar 39, which serves to hold the cord 37 taut and resultantly the music sheet is held in position.

It is obvious that in this manner the music sheet may be quickly adjusted upon the rack and held in position so that the leaves will not become deranged or blown off.

The device may be quickly detached from the music stand or rack by the adjustment of the wing bolts 9 and 10 and the attachment may be folded up for insertion into

the pocket or into the instrument-case with the foldable rack.

Having thus fully described my invention, 45 what I claim as new and desire to secure by Letters Patent is:—

1. The combination with a music rack, of a music sheet holding device comprising a central bar member adapted for detachable connection to said central bar, a pair of arms pivotally connected to said bar member, a pair of arms pivotally mounted on the free ends of the first mentioned bars, spring clips arranged on the second mentioned bars, 50 the first mentioned bars formed with rack teeth, a pair of pawl members pivotally connected to the bar member, and said pawl members adapted for engagement with the rack teeth for holding said arms in adjusted 55 position.

2. The combination with a music rack, of a music sheet holding device comprising a central bar member adapted for detachable connection to said central bar, a pair of 60 arms pivotally connected to said bar member, a pair of arms pivotally mounted on the free ends of the first mentioned bars, spring clips arranged on the second mentioned bars, the first mentioned bars formed with 65 rack teeth, a pair of pawl members pivotally connected to the bar members, said pawl members adapted for engagement with the rack teeth for holding said arms in adjusted position, and a flexible element 70 secured to the upper end of the central bar and having a clip attached to one end adapted for engagement with the rack.

In witness whereof I have hereunto set my hand.

FREDERICK WILLIAM McNICHOL.
